UNITED STATES PATENT OFFICE.

SUSAN H. DECOU, OF CENTREVILLE, OHIO.

WINDOW-FRAME.

SPECIFICATION forming part of Letters Patent No. 224,818, dated February 24, 1880.

Application filed April 14, 1879.

To all whom it may concern:

Be it known that I, SUSAN H. DECOU, of Centreville, in the county of Montgomery and State of Ohio, have invented certain new and useful Improvements in Window-Frames; and I do hereby declare the following to be a full, clear, and exact description of the same.

My invention has for its object an improvement in the construction of window-frames; and it relates to that class of frames in which the sash-beads are retained in place by adjustable fastenings.

The novelty consists in the arrangement and construction of a metal spring for holding the bead and securing it to the frame, as will be herewith set forth and specifically claimed.

In the accompanying drawings, Figure 1 is a perspective view of the sash-retaining strip or bead. Fig. 2 is a front elevation of one side of the window-frame, with portions cut away to show the construction and arrangement of my devices. Fig. 3 is a perspective view of the retaining-spring.

Corresponding letters of reference indicate like parts in all the figures.

A, Fig. 1, is a window strip or bead of the ordinary shape. Upon the inner side of this strip is a small metal staple, *a*, set transversely, and fastened near the middle of the strip, as indicated.

If desired, the lower end of the bead may be provided with a tenon, *b*, as shown.

The sill *B*, Fig. 2, of the frame is mortised at *c*, just where it joins the side piece, *C*, of the frame, to receive the lower end or tenon of the bead when placed in its proper position, and the little *D* is also mortised at *d*, to receive the upper end of the bead. This upper mortise is deeper than the lower one, to allow the bead to be slipped up when applying it to the frame.

Recessed into the side of the frame, in line

with the staple on the bead, and secured by screws, is the combined retaining hook and spring *E*, Figs. 2 and 3. This latter is a thin metal plate having its upper end so shaped 45 that the staple on the bead can fit snugly over it, while its lower end forms a projecting spring, which, when the bead is in place, fits into a notch or mortise, *e*, Fig. 1, in the edge 50 of the bead, and prevents its slipping up off of the hook. The lower mortise prevents any downward movement of the bead, which is thus securely held from displacement at its top, bottom, and middle.

To remove the bead, when it is desired to take out the sash for any purpose, it is only necessary to depress the inner exposed part of the spring, which then allows the bead to be slipped up into the mortise *d* sufficiently to 60 slip the staple off the hook and disengage the lower end of the bead from the sill-mortise. By simply drawing the bead out at its lower end and pulling it down its removal is instantly effected.

In long windows two or more of these spring-hooks may be employed, if desired.

Having thus fully described my invention, I claim—

1. In a window-frame, the sash-retaining strips or beads provided with a staple, in combination with the retaining hook and spring *E*, constructed and applied in the manner and for the purpose specified.

2. In a window-bead fastening, the spring- 75 hook *E*, one portion of which forms a hook and the other portion a spring, as and for the purpose specified.

Witness my hand this 3d day of February, A. D. 1879.

SUSAN H. DECOU.
